ADJUSTABLE FOLDABLE SCAFFOLD

Milo S. Franklin, Marshalltown, Iowa

Application December 14, 1954, Serial No. 475,092

1 Claim. (Cl. 304—5)

The present invention relates to new and useful improvements in scaffolds adapted for use by paper hangers, carpenters and other workmen, and more particularly to a vertically adjustable and foldable scaffold of this character.

An important object of the invention is to provide a foldable leg structure on top of which a clamping member is supported for a plank which forms a platform on which the workman stands.

Another object of the invention is to provide a laterally extensible plank clamping member for securing planks of various widths thereto.

A still further object is to provide a vertically adjustable inverted U-shaped leg structure at the top of which the plank clamping member is swingably mounted for folding downwardly in a position parallel to the legs for conveniently handling and storing the same.

A still further object is to provide a device of this character of simple and practical construction, which is strong and durable, relatively inexpensive to manufacture and otherwise well adapted for the purpose for which the same is intended.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view showing the plank clamping member raised for supporting a plank thereon;

Figure 2 is an enlarged fragmentary vertical sectional view taken on a line 2—2 of Figure 1;

Figure 3 is a fragmentary and elevational view;

Figure 4 is a bottom plan view showing the legs folded against the bottom of the plank; and

Figure 5 is a side elevational view showing the scaffold in folded position.

Referring now to the drawings in detail wherein for the purposes of illustration, I have disclosed a preferred embodiment of my invention, the numeral 5 designates an inverted U-shaped leg structure of tubular metal and having a plurality of telescoping sections 6 at its lower end and formed with aligned openings 7 to receive bolts and wing nuts 8 for securing the leg structure in vertically adjusted position.

The top of the leg structure includes a cross-bar 9 which unites the upper portion of the pair of legs 11 and 12 to each other and on which a clamping member designated generally at 13 is swingably supported. The clamping member 13 includes a pair of sheet metal plates 14 and 15 positioned in overlapping relation with respect to each other, and the lowermost plate 14 is formed with a pair of transversely extending slots 16 to adjustably receive bolts and wing nuts 17 extending downwardly from plate 15 to secure the plate in laterally extensibly adjusted position with respect to each other.

2

A pair of strap metal bearing brackets 18 have their end portions welded or otherwise suitably secured to the underside of plate 14, and the central portions of the bearing brackets 18 are formed with bearing eyes 19 in which the cross-member 9 of the leg structure is positioned for swingably mounting the clamping member 13 thereon.

The side edges of the plates 14 and 15 are formed with opposed channels 20 and 21, respectively, positioned above the plate to receive the opposite side edges of a plank 22. The lateral adjustment of the plates 14 and 15 enables planks of various widths to be clamped in the channels of the clamping member.

Sleeves 23 and 24 are slidably mounted, respectively, on the legs 11 and 12 and a pivoted brace 25 is connected at its lower end to the sleeve 23 and is connected at its upper end to the underside of plate 14 adjacent one end portion of the latter. A similar pivoted brace 26 connects sleeve 24 to the underside of plate 15.

A U-shaped brace 27 is pivoted at its end portion to the sleeves 23 and 24 and is formed with a transversely extending slot 28 at its right portion to receive one of the bolts and wing nuts 17 at the end portion of plate 14 opposite to the pivotal connection of the braces 25 and 26. The braces are sufficiently resilient to permit adjustment of the plates.

In the operation of the device, when the scaffold is to be erected, the clamping member 13 is swung into a horizontal position at the top of the leg structure 5 and the swinging of the clamping member into a horizontal position slides the sleeves 23 and 24 upwardly on the legs 11 and 12 so that one of the bolts and wing nuts 17 may be engaged in the slot 28 of the brace 27 to secure the clamping member in its erected position. The plank 22 may then be placed in the channels 20 and 21 of the clamping member and two or more of the leg structures 5 and clamping members 13 may be provided to adequately support and brace the plank from sagging movement. The extensible adjustment of the lower leg sections 6 enables the plank to be supported at a desired elevated position.

By releasing the brace 27 from the clamping member, the legs may be swung upwardly against the underside of the plank, as shown in Figures 4 and 5, and with the clamping members 13 positioned parallel to the legs, so that the scaffold may be conveniently carried with the plank remaining attached thereto, or the plank may be removed from the clamping member and the legs and clamping member folded against each other.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claim.

60 What is claimed as new is as follows:

A scaffold comprising a plank, a pair of overlapping upper and lower plates engaging each other and supporting the plank and having confronting channel flanges clampingly engaging opposite side edges of the plank, said plates being slidably adjustable relatively transversely of the plank to adjust said flanges into and from clamping engagement with said side edges of the plank, an inverted U-shaped pair of legs having a right portion beneath said plates, bearings on the lower plate 65 in which said right portion is journaled for swinging of said legs into and from supporting relation to the lower plate, and slot and bolt means in said plates for 70

retaining the plates in adjusted position and connecting said plates together for guided sliding adjustment.
